UNITED STATES PATENT OFFICE

OZRO A. HILLMAN, OF PROVIDENCE, RHODE ISLAND.

IMPROVEMENT IN HARVESTER-CUTTERS.

Specification forming part of Letters Patent No. 150,319, dated April 28, 1874; application filed February 10, 1874.

To all whom it may concern:

Be it known that I, OZRO A. HILLMAN, of the city of Providence, and county of Providence, in the State of Rhode Island, have invented certain new and useful Improvements in the Cutting Apparatus for Mowing-Machines.

My invention consists, partially, in the method of mounting the bearing-blocks on the finger-bar, whereby they may be readily adjusted or displaced for renewal; also, in combining, with the bearings and sickle-button, a lubricating-chamber provided with ducts communicating with the bearings; and, still further, in certain other minor points, hereinafter described; and I do hereby declare that the following specification, taken in connection with the drawings furnished and forming a part of the same, is a clear, true, and accurate description of my said invention.

In the drawings, Figure 1 represents in the top view a portion of a finger-bar with sickle and my improvements attached. Fig. 2 represents, in vertical lateral section, one of the fingers, sickle-sections, the sickle and its bearings, and the lubricating-chamber. Fig. 3 represents the sickle-button, lubricating-chamber, and bearing-clamp in vertical longitudinal section. Fig. 4 represents, in front view and section, the rectangular bearing which is attached to one of the sickle-sections. Fig. 5 represents a bearing-block detached from its clamp. Fig. 6 illustrates the movement of the ends of the knife-sections.

In each instance, A denotes the finger-bar, having well-known characteristics, which involve none of the features of my invention. B denotes the ordinary sickle-sections. C denotes the sickle, which may be actuated by any of the well-tried operative mechanisms. D denotes a bearing-block clamp, which also, with its projecting arm *a*, performs the functions of a scythe-button. This clamp is secured to the upper surface of the finger-bar by bolts or heavy screws, as seen at *b*, which may also be employed for uniting the fingers to the finger-bar. Within the upper portion of the clamp is a lubricating-chamber, E, provided with a suitable cap or cover, and a duct, as at *c*, at the bottom thereof. F denotes a rectangular bearing, composed of hardened metal,

and having a length slightly greater than the limits within which the sickle is capable of being moved longitudinally. The bearing is firmly united to the rear edge of the sickle; and for giving it additional firmness, sections of the sickle corresponding in number and position with the bearing-blocks are of such a length as to project their rear ends over the edge of the sickle-bar about one-fourth of an inch, and to the under side of these projections the rectangular hardened-steel bearings are riveted. These bearings, when the sickle is in proper working position, are in frictional contact with the front and upper faces of the bearing-blocks, thereby relieving from friction and wear all portions of the sickle-bar, as well as all of the sickle-sections, except the cutting-edges thereof. The rectangular bearings F being separately constructed and secured to the sickle-bar, as described, it is possible to readily renew them when unduly worn, the bar meantime remaining intact instead of being worn away, as would be the case if the stationary bearings were in direct contact therewith. G denotes the bearing-block, which is bound to the finger-bar by means of the clamp D and its bolts. Its thickness is such, when compared with the height of the recess of the clamp, that by turning on the bolts the bearing-block will be firmly held in position. Each flat side of the block, near its front edge, has a surface duct, as at *d*, for the passage of oil. The bearing-blocks and the rectangular bearings may be made of hardened steel, or the bearing-block may be made of hard bronze or other equally non-corrosive metal adapted for use in connection with slidebearings. When, by reason of wear on the front faces of the blocks, it is desirable to advance them slightly, it can be readily accomplished by slightly loosening the bolts and driving the blocks inward to the desired point. When the upper front surface of the blocks become worn they can be taken out, turned over, and replaced, thus affording an opportunity for both sides to be equally worn before their renewal becomes desirable. It will be seen that the lubricating-chambers can be supplied with a fibrous absorbent and fine oil in proper quantities, and that it will be conducted directly to the exact points where it is required. Figs.

2 and 6 clearly illustrate the action of the knife-sections. The under sides of the knives are not in general contact with the entire upper surface of the lateral slope in the fingers, as in machines not possessing my improvement, but, on the contrary, each of the knives bears only on one or both of the coincident shear-edges of the two adjacent fingers, and during the longitudinal movement of the sickle-bar the outer ends of the knife-sections move slightly down and up, as illustrated by the dotted lines at *e* in Fig. 6. This arrangement of the sickle-bar, bearings, and the cutters with relation to the longitudinal upper surfaces of the slots in the fingers secures at every portion of the stroke a perfect shear contact of each knife-edge with the adjacent shear-edge of the finger, and results in a clean and perfect cut. The bearing-block clamp will, preferably, be secured to the finger-bar by means of the bolts, which also perform the function of securing two of the adjacent fingers to the bar, it only being essential that the bolts be made sufficiently longer than usual, so as to properly engage therewith. The bearing-block clamp being formed in one piece

with the scythe-button, and the bearings being adjacent thereto, economy in construction to a desirable degree is attained. The presence of the scythe-button adjacent to the bearings serves, in a measure, to protect the bearings from dirt, and to keep the bearing-surfaces in proper contact.

Having thus described my invention, I claim as new, to be secured by Letters Patent—

1. The combination, with the bearing-blocks *G*, of the clamp *D*, whereby the blocks are secured to the finger-bar and rendered capable of ready adjustment and renewal, substantially as described.

2. The lubricating-chamber mounted on the finger-bar, located adjacent to the sickle-bearings, and provided with a duct for conveying oil to the said bearings, substantially as described.

3. The rectangular bearings *F*, separately constructed and secured to the sickle-bar, substantially as described.

OZRO A. HILLMAN.
